United States Patent [19]

Takahashi et al.

[11] Patent Number: Des. 286,541

[45] Date of Patent: ** Nov. 4, 1986

[54] **PHOTOCONDUCTOR UNIT FOR COPYING MACHINE**

[75] Inventors: Sadao Takahashi, Tokyo; Minoru Suzuki, Kanagawa, both of Japan

[73] Assignee: Ricoh Company, Ltd., Japan

[**] Term: 14 Years

[21] Appl. No.: 648,712

[22] Filed: Sep. 7, 1984

[30] **Foreign Application Priority Data**

Mar. 7, 1984 [JP] Japan 59-008642

[52] U.S. Cl. D16/32; D16/27

[58] Field of Search D16/27-32; 355/3 R, 3 DR, 3 DD

[57] **CLAIM**

The ornamental design for photoconductor unit for copying machine, as shown.

DESCRIPTION

FIG. 1 is a left front perspective view of a photoconductor unit for copying machine showing my new design;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof; and,

FIG. 7 is a bottom plan view thereof.

FIG. 1

FIG. 2

FIG. 4

FIG. 3

FIG. 5

FIG. 6

FIG. 7
